(57) CLAIM

The ornamental design for a football-themed beverage container, as shown and described.

DESCRIPTION

FIG. 1 is a front view of a football-themed beverage container of the present design;
FIG. 2 is a rear view of the football-themed beverage container of the present design;
FIG. 3 is a right side view of the football-themed beverage container of the present design;
FIG. 4 is a left side view of the football-themed beverage container of the present design;
FIG. 5 is a top rear perspective view of the football-themed beverage container of the present design;
FIG. 6 is a bottom front perspective view of the football-themed beverage container of the present design;
FIG. 7 is a top view of the football-themed beverage container of the present design;
FIG. 8 is a bottom view of the football-themed beverage container of the present design; and,
FIG. 9 is a bottom perspective view of the football-themed beverage container of the present design, wherein the container is tilted more horizontally than in FIG. 6 and wherein the front of the container is oriented upwardly.
The broken lines show portions of the football-themed beverage container that form no part of the claimed design.

1 Claim, 9 Drawing Sheets
